(Cl. D62—2)

To all whom it may concern:

Be it known that we, Eric Gustafsson and John W. Baur, both citizens of the United States, and residing in Chicago, county of Cook, and State of Illinois, have invented a new, original, and ornamental Design for an Antioffset Dry Powder Gun or the like, of which the following is a specification reference being made to the accompanying drawings forming a part thereof.

Fig. 1 is a side elevational view of an anti-offset dry powder gun or the like, showing our design;

Fig. 2 is a rear elevational view thereof; and, Fig. 3 is a top plan view thereof.

We claim:

The ornamental design for an antioffset dry powder gun or the like, as shown.

ERIC GUSTAFSSON.
JOHN W. BAUR.
